FIREPROOF FUEL TANK SYSTEM

Brooks Walker, Piedmont, Calif.

Application March 10, 1943, Serial No. 478,657

3 Claims. (Cl. 220—88)

(Granted under the act of March 3, 1883, as
amended April 30, 1928; 370 O. G. 757)

The invention described herein may be manufactured and used by or for the Government for governmental purposes without the payment to me of any royalty thereon.

This invention relates to a system for making the fuel tank of a self-propelled vehicle substantially fireproof. The invention relates particularly to combat aircraft, although it is of course not so limited in its use.

A perpetual nightmare for a pursuit pilot or the crew of a bomber is the possibilities for fire which are inherent wherever gasoline is present, especially the highly volatile gasolines used in planes. It has been found that the air-vapor mixture above the liquid in the tank is likely to be explosive when the tank is from 5% to 50% full, and at -10° F. or colder. These are, of course, precisely the conditions likely to be encountered in combat. It may be noted that these specifications may vary with the kind of gasoline. In general, however, explosive mixtures form when the tank is about half or less than half full, and when the temperature is low enough to reduce the vapor pressure of the gasoline to the point where the vapor space is not filled completely with gasoline vapor.

It is the object of this invention to provide a fuel system in which the danger of fire from bullets, including tracers and incendiaries, piercing the tank is substantially reduced. This object is accomplished by keeping the vapor space above the liquid filled with an inert gas. This gas is supplied from the exhaust of the internal combustion engine or other power plant which drives the vehicle or vehicle auxiliaries. Means are provided to cool the gas and to insure that sparks and moisture will not pass to the vapor space.

Figure 1 of the drawing shows a preferred embodiment of the invention, in which a water-cooled internal combustion engine provides the exhaust gas for the fuel tank vapor space.

Figure 2 is a fragmentary view of a modified form of my invention.

Referring to the drawing in detail, a fuel tank is shown at 2, having a quantity of fuel 4 in it. The space 6 above the tank is adapted to be filled by an inert gas, which is preferably provided by by-passing some of the exhaust gas from the power plant 8 of the vehicle. Power plant 8 is provided with an exhaust gas outlet conduit 10. A by-pass connection 12 takes some gas from conduit 10 to fill the vapor space 6. The gas-entrance end of connection 12 is preferably pointed upstream as shown at 14 to give the by- 55

passed exhaust gas the benefit of the kinetic energy of the gas in conduit 10.

Any suitable flame or fire screen, or spark arrester, will preferably be provided at 16. To condense a major portion of the water vapor out of the gas, a cooler 18 is provided. A trap 20 in the lower part of the cooling coil is provided with a drip 22 to permit the discharge of condensed moisture. Such water vapor as is not thus removed is taken out in a suitable dehydrator 24.

If necessary, a pump 26, such as a centrifugal pump, may be provided in connection 12 to boost the pressure of the gas going to the tank. A hand valve 28 may conveniently be provided to permit isolation of the tank from the exhaust gas conduit.

In order to permit a continuous flow of exhaust gas through the vapor space 6 and to prevent building up too great a pressure in the tank when the plane climbs rapidly, a low positive pressure relief valve 30 is preferably provided in the upper wall 32 of the tank. It will be understood that a conduit, not shown, may be provided to carry the discharged exhaust gases away from the tank, rather than simply dump those gases out through valve 30. A check valve 33 is provided to prevent gasoline fumes flowing back into the dehydrator, cooler and exhaust line.

The tank 2 is provided with the conventional capped fuel inlet 34. Suitable baffles as shown at 36 may be provided to keep fuel from sloshing out through valve 30.

In operation, particularly in pursuit planes, ascent and descent are likely to be very fast at times, resulting in some rather rapid atmospheric pressure changes. In a power dive, the pressure outside tank 2 will rise rapidly, necessitating a fast build-up of internal pressure by the exhaust gas to prevent collapsing the tank. The connection 12 should therefore have sufficient carrying capacity to be able to supply exhaust gas to the tank as fast as it is required to maintain the desired pressure differential.

It can thus be seen that the usual explosive mixture above the liquid in the tank is supplanted by an inert gas, thus substantially reducing the fire hazard in case bullets should pierce the tank.

Under some circumstances, it may be desirable to have a pressure less than atmospheric in the vapor space above the tank. This negative pressure should be enough to overcome the static head of fuel, as explained in detail in my previous case, Serial No. 439,533, filed April 18, 1942. In the event that a vacuum or a pressure less than atmospheric pressure is desired in the tank, an

arrangement as shown in Figure 2 may be provided wherein a suction pump 50 is disposed in the connection 12 in a direction reversed to that of the pump 28 shown in Figure 1. It will be evident that as the fuel in the tank is consumed, the gases will occupy a greater volume of the tank with resultant lower pressures. There is usually a partial vacuum produced by the lowering of the fuel in the tank and with the help of a suction pump in the connection between the exhaust line and the fuel tank, it will be evident that a partial vacuum can be maintained. A partial vacuum in the fuel tank reduces the shocking effect of the fuel tank materially when it is penetrated by high velocity bullets or fragments. The partial vacuum also reduces the tendency of the fuel to leak out of the tank. Exhaust gas will flow against the pump into the vapor space, the pump serving merely to maintain a predetermined differential between the atmospheric pressure and the pressure in the tank.

It will be evident from the foregoing that I have provided a novel combination of devices between the exhaust line of an internal combustion engine and a fuel tank for high volatile fuel wherein the hot inert gases from the exhaust line are cooled, dehydrated, and run through a pump or a pressure control valve (not shown) into the

tank above the volatile fluid to prevent fire therein.

Various changes may be made in the specific embodiment of my invention without departing from the spirit thereof, or from the scope of the appended claims.

I claim:

1. In combination with a storage tank for high volatile fuels and the exhaust line of an internal combustion engine, a fluid connection therebetween having in seriatim from said exhaust line to said storage tank, a cooler, a dehydrator, a pump, and a check valve, said check valve permitting inflow of inert exhaust gases into said storage tank but preventing outflow of fluid from said storage tank.

2. A system as set forth in claim 1 wherein said connection has a spark arrester disposed therein immediately adjacent said exhaust line.

3. In combination with a storage tank for high volatile fuel and the exhaust line of an internal combustion engine, a fluid connection therebetween having in seriatim from said exhaust line to said storage tank, a cooler, a dehydrator, a suction pump, a hand valve, and a check valve, said suction pump tending to maintain the pressure in said storage tank below atmospheric pressure.

BROOKS WALKER.
